UNITED STATES PATENT OFFICE.

MAX F. KIESSLING, OF WATERBURY, CONNECTICUT, ASSIGNOR TO AMERICAN FASTENER COMPANY, OF WATERBURY, CONNECTICUT, A CORPORATION OF CONNECTICUT.

SNAP FASTENER.

Application filed April 25, 1922. Serial No. 556,509.

To all whom it may concern:

Be it known that I, MAX F. KIESSLING, a citizen of the United States, and a resident of Waterbury, county of New Haven, and 5 State of Connecticut, have invented certain new and useful Improvements in Snap Fasteners, of which the following is a specification.

This invention relates to separable fasteners and more particularly to an improved 10 form of socket member for use in a snap-fastener of the stud and socket type.

One object of the invention is to provide an improved form of socket member for 15 such a snap-fastener in which it will be practically impossible for the washer and base member to work loose or come apart under ordinary service conditions.

A further object is to provide a snap- 20 fastener of the above nature which will be simple, cheap to manufacture, and very efficient and durable in use.

With these and other objects in view, there has been illustrated on the accompanying drawings one form in which the invention may be conveniently embodied in practice.

Fig. 1 represents a transverse sectional 30 view of the snap-fastener, showing the appearance of the socket member and washer before the dome of the shank has been headed over into the annular seat of the washer.

Fig. 2 is a similar transverse view of the snap-fastener showing its appearance after 35 the dome has been headed over into the annular seat of the washer, and also showing the cooperating stud member in position, detachably secured to said socket member.

Fig. 3 is a top plan view of the base 40 of the socket member detached from its washer, as it appears before the heading operation.

Fig. 4 is a side sectional view of the top 45 portion of the shank of the socket member as it appears when the head is being formed by means of a die and punch.

In the previous forms of stud and socket fasteners, in which a washer was employed 50 to hold the fabric to the base of the socket member, said fabric was sometimes secured to the base by an open eyelet shank which was flanged over upon the washer. In other cases, the fabric was held in position by

means of a smooth cylindrical shank, closed 55 at the top, which was headed over upon the washer. Both of these old forms of fastener, however, have proven unsatisfactory in practice.

In the first mentioned form having the 60 shank open at the top, it was found that while the fabric was being washed, moisture would collect in the tubular shank of the fastener, a small amount of which would remain in the fastener after the fabric was 65 dried, causing the socket to rust or oxidize. Moreover, dirt often became lodged in the open shank, and as a consequence, the snap-fastener became unsightly as well as unsanitary. 70

With the second mentioned previous form of fastener—i. e. that in which the socket member had a smooth cylindrical shank—it was found that during the process of heading over the top of the shank, the metal had a 75 tendency to crack, split, or buckle over unevenly. This caused an unsatisfactory joint between the top of the shank and the washer, causing the washer to work loose or break entirely away from the base. 80 Hence with such a fastener, it was impossible with such a fastener, it was impossible for the manufacturer to sell the fastener with a guarantee that the washer would stay on the base.

The present invention is designed to overcome the above and other disadvantages. This has been accomplished by the use of a socket member having a tubular shank with a closed top or dome, and provided with a grooved neck portion, immediately below 90 the dome. It has been discovered that when the dome of such a shank is headed over into the washer, the metal will not crack, split, or buckle, as is generally the case with a straight shank, but will be 95 spread apart uniformly to form a smooth circular head. The joint thus formed between the washer and the head of the shank has been found to be extremely strong and reliable, and it is now possible for the manufacturer to give a strong guarantee against the separation of the washer from the base member of the fastener. 100

Referring now to the drawings in which like reference numerals denote corresponding parts throughout the several views, the numeral 10 represents the circular plate or base portion of the socket member having

a central tubular shank 11 rising upwardly and formed integral with the base 10. The base 10 is provided on its outer circumference with an upwardly and inwardly 5 rolled flange 12 enclosing a spring device formed of a single piece of spring wire. The wire spring device consists of a semi-circular body portion 13, a pair of reversely bent portions 14, 14, and a pair of parallel 10 free arm sections 15, 15.

The free arm sections 15, 15, of the spring device are adapted to lie within a pair of oppositely alined slots 16, 16, formed at the base of the shank. As will be evident, 15 the free arms 15, 15, are adapted to resiliently press upon the stud member of the snap-fastener below the dome 27, whereby the socket and stud members will be detachably locked together.

20 The upper end of the shank 11 is closed and is formed into the shape of a sphere or a dome 17, below which is a necked portion 18 for a purpose to be hereinafter more fully described. Surrounding the shank 11 immediately adjacent the neck portion 18 is 25 a circular washer 19 having an annular central depressed seat 20, into which the dome 17 is adapted to be flattened down during the heading operation, as clearly shown in Fig. 30 2. The washer 19 is provided with a downwardly tapered rim or cupped section 21 having its edge bent inwardly and adapted to engage an upper fabric 22 and hold said fabric rigidly in position upon the base 10.

35 The stud member of the snap-fastener, which cooperates with the socket member, comprises a base plate 23 and a top plate 24, between which plates the fabric 25 is adapted to be engaged. Extending upwardly 40 from the top plate 24 is a shank 26 having an enlarged dome 27 at the top. As will be evident from Fig. 2, the shank 26 is adapted to be releasably engaged by the parallel free arms 15, 15 of the spring device extending 45 through the slots 16, 16.

While this invention is especially adapted for use in connection with the manufacture of "fabric fastener tapes," having rows of cooperating fastener members secured thereto, the improved fasteners may also be secured directly to the edges of the goods to be 50 detachably joined.

In operation, when it is desired to attach a snap-fastener to a fabric, a hole may be 55 pierced in the fabric at the point where the fastener is to be applied. The tubular shank 11 of the socket member is then inserted through the hole in the fabric, and the washer 19 is slipped down 60 around the shank until it engages the top of the fabric. The next operation is to flatten the dome 17 down upon the annular seat 20 of the washer 19 until it presents a flat head flush with the top surface of said 65 washer. This heading process is preferably

accomplished in a press by means of a punch 28 and die 29 in the manner illustrated in Fig. 4, but the heading may also be efficiently done simply by the use of a pair of pliers, the cooperating jaws of which are 70 provided with die and punch members respectively. One advantage of this invention is the simplicity and ease with which the heading may be accomplished, no special form of heading machinery being required. 75

It will be understood that while this invention is especially adapted for dress fasteners, it may also be used to connect the edges of gloves, automobile curtains, upholsterry, slip-covers, etc. 80

While there has been disclosed in this specification, one form in which the invention may be embodied, it is to be understood that this form is shown for the purpose of illustration only, and that the invention is 85 not to be limited to the specific disclosure, but may be modified and embodied in various other forms without departing from its spirit. In short the invention includes all the modifications and embodiments coming 90 within the scope of the following claims.

Having thus fully described the invention, what is claimed as new, and for which it is desired to secure Letters Patent, is:

1. In a snap-fastener, a stud member, a 95 socket member for detachably receiving the end of said stud member, said socket member comprising a base, a shank, and a washer, said shank being closed at the top and provided, with a reduced neck portion intermediate its length, the top of said shank being adapted to be headed over upon said washer, the diameter of the closed top and the bottom of said shank being substantially the same in their original condition, before the 100 top of the shank has been headed over upon the stud member.

2. In a stud and socket fastener, a stud member, a socket member cooperating therewith, and comprising a base plate, a shank 110 extending upwardly from said base plate, a spring device on said base plate extending through the wall of said shank for engaging said stud member to detachably hold said stud and socket members together, said shank having its upper end closed to form a dome, and having a reduced neck portion, a washer upon which said dome is adapted to be headed over, the diameters of the dome and bottom portion of the shank being substantially the same in their original condition. 115

3. In a snap-fastener, a stud member, a socket member for detachably receiving the end of said stud member, said socket member comprising a base plate and a washer, said base plate having an upstanding tubular member integral therewith, said tubular member being closed at the top and being reduced in diameter adjacent its top to form 120

an annular groove, the top of said tubular member being adapted to be headed over upon said washer to detachably lock the washer to the base plate.

5. In a snap-fastener, a stud member, a socket member for detachably receiving said stud member, said socket member comprising a base having a central upstanding tubular shank, said shank being closed at the 10 top, and provided with an annular groove, a washer, the portion of said shank above said groove being adapted to be flattened down upon said washer.

5. In a snap-fastener, a stud member, a 15 socket member for detachably receiving said stud member, said socket member comprising a base having a central upstanding tubular shank, said shank being closed at the top, and provided with an annular groove, a

washer, said washer having an annular depression at the center, the top of said shank being adapted to be flattened down above said groove into the depression of said washer.

6. In a socket member for a stud and socket fastener, a base, a shank secured to said base, a washer mounted on said shank and adapted to engage a fabric located between said washer and base, said shank having substantially the same diameter throughout its 30 length except for an intermediate reduced neck portion and a closed dome above said neck portion, said dome adapted to be flattened down above said neck portion to form a head upon said washer.

In testimony whereof, I have affixed my signature to this specification.

MAX F. KIESSLING.
